UNITED STATES PATENT OFFICE

CORNELIUS R. UMBENHOWER, OF ANDERSON, INDIANA.

VAPOR OIL-BURNER.

No. 827,764.

Specification of Letters Patent.

Patented Aug. 7, 1906.

Application filed July 22, 1903. Serial No. 166,645.

To all whom it may concern:

Be it known that I, CORNELIUS R. UMBENHOWER, of Anderson, county of Madison, and State of Indiana, have invented a certain new and useful Vapor Oil-Burner; and I do hereby declare that the following is a full, clear, and exact description thereof, reference being had to the accompanying drawings, in which like numerals refer to like parts.

10 The object of this invention is to provide improvements in devices for burning oil as fuel which promote the complete vaporization and combustion of the oil and which has by reason of its construction means for conveniently using it, especially in cooking-stoves, for which it is best adapted.

15 The full nature of the invention will be understood from the accompanying drawings and the following description and claim.

20 In the drawings, Figure 1 is a perspective of the device. Fig. 2 is a central vertical longitudinal section thereof. Fig. 3 is a plan view with the combustion-chamber, top portion, and dripping-pan removed.

25 10 represents a pipe leading from any suitable supply of oil, such as kerosene or the like. 11 is a pipe leading therefrom horizontally and then vertically into the burner. 12 is a valve. The upper end of the pipe 10 is 30 threaded at 13 to receive a dome 14, having a central hole 15 through it for the admission of the oil. The dome, while hollow, is rather thick and solid, especially in the upper portion, so that it will hold considerable heat, 35 and about its base there is a series of vertical air-holes 16.

Under the pipe 11 there is a dripping-pan 40 17, preferably scalloped at 18 along one side, so the air may freely pass from the front of the stove in which the burner may be located to the burner. There are four stands or supports 19, secured equidistant from each other in said dripping-pan, and notched or shouldered to receive what may be termed an

45 "oil-pan" 20, that is cylindrical, having an outward rim and also an inward rim centrally through which the inner and upper end of the pipe 11 extends loosely. This inner portion of the oil-pan is provided on each side with a 50 large air-opening 21, and it is also provided between the inner and outer ends with a series of upwardly-extending tubes 22 to provide air-inlet openings 23. The rims and tubes 22 extend upward for the purpose of preventing 55 the escape of oil from said pan 20 when it

runs down from the dome as the burner is being started.

Within the oil-pan 20, at the top thereof, a cylindrical casing 25 rests loosely, the upper end thereof being contracted, so that said 6 casing extends around the dome 14 and forms a chamber about the same with a contracted upper opening. Said casing has in it peripheral slots 26, through which the flame also passes.

65 A large combustion-chamber, 30 rests loosely upon the oil-pan 20. The lower portion is cylindrical; but the upper portion is enlarged in two opposite directions, so as to be longitudinal, as shown in Fig. 2, the 70 length being preferably about twice the width. This is closed, excepting at the top, which has a number of outlet-holes 31, distributed throughout the top, and two large outlet-openings 32, one at each end. These latter 75 openings are covered by deflectors 33, that are supported on legs 34, that are notched at their lower ends and rest loosely within the openings 32 and on the top of the chamber 30. There is also a cap 35, pivoted on the 80 top by the pin 36 for closing the central opening 37. This latter is for the purpose of rendering the interior accessible for lighting and cleaning it out readily.

75 From this description it is observed that this oil-burner is readily constructed or taken apart, as the parts in the main rest loosely in place. On the rear side of the burner, as it is located in a stove, there are preferably a pair of outlet-openings 38 in the chamber 30, 90 as seen in Fig. 1, that are opened and closed by the damper 39, held in place by the screw 40, extending through the slot 41. This damper has a hole 42 in it to register with one of the holes 38. As shown in Fig. 1, the 95 damper is in position to open the holes 38, but by moving to the left it will close said openings.

The operation is as follows: The device is mounted in, preferably, a cooking-stove with 100 the side shown in Fig. 1 having the scallops in the bottom or drip-pan toward the front of the stove and the openings 38 toward the back or oven of the stove. The valve 12 is opened and oil conveyed through the oil-pipe 105 11, which runs down over the dome 14, and it may flow down into the oil-pan 20. The cap 35 is turned sidewise and a match dropped inside for igniting the oil. The cap 35 is then moved back to its closing position. 110

The oil will accumulate in the pan 20 and burn, but will soon heat the upper end of the pipe 11, and especially the thick dome 14, sufficiently to vaporize the oil as it passes out 5 of the pipe 11, and thereafter the oil will not flow more than one-half of the way down the dome 14 before it is vaporized. The air for supplying oxygen comes in a considerable quantity through the openings 23 and passes 10 upward within the casing 25 and is deflected by it in against the dome and there mixed with the vapor. The most of the vapor during combustion passes upward from the dome, although there is a tendency of a portion of it 15 to pass down through the little openings 16, surrounding the base of the dome, which increases the heat of the dome and of the air approaching the dome and promotes the admixture of air and vapor within the casing 20. The flame passing upward from the dome strikes the top and is deflected laterally in every direction and passes out 25 through the small holes and the large openings 32 at the ends of the chamber 30. With this arrangement of the chamber 30 the further, final, and complete admixture of air and gas is effected in said chamber, so that 30 all the gas is consumed and a smokeless flame issues through the openings and outlets from said chamber. If it is desired to heat the oven of the stove, the damper 39 is moved to the position shown in Fig. 1, so that the flame rushes out rearward through the openings 38 directly against the oven; but when the oven is not in use said damper is closed, which 35 causes all of the flame to pass upward.

What I claim as my invention, and desire to secure by Letters Patent, is—

An oil-burner comprising means for supplying oil thereto, a dome surrounding the outlet over which oil may flow, a series of upwardly-extending open tubular projections 40 surrounding the base of the dome, an oil-pan with a series of upwardly-extending open tubular projections for the admission of air, a casing surrounding said dome contracted at 45 its upper end to form a chamber between it and the dome, a mixing-chamber above said dome provided with outlet-openings in the top and sides thereof, a damper for closing 50 the side openings, a removable cap for closing the top opening over said dome, and deflectors over the other top openings, substantially as set forth.

In witness whereof I have hereunto affixed, 55 my signature in the presence of the witnesses herein named.

CORNELIUS R. UMBENHOWER.
